Primary Examiner—Louis S. Zarfas*Assistant Examiner*—Monica A. Weingart[57] **CLAIM**

I claim the ornamental design for a fixed rear sight for revolvers, as shown.

DESCRIPTION

FIG. 1 is a view in rear perspective, showing the design for a fixed rear sight for revolvers.

FIG. 2 is a top plan view thereof.

FIG. 3 is a bottom plan view thereof.

FIG. 4 is a view in front elevation thereof.

FIG. 5 is a left side elevation thereof.

FIG. 6 is a view in rear elevation thereof; and,

FIG. 7 is a view in right side elevation thereof.
